(57) CLAIM

The ornamental design for a light with integrated camera, as shown and described.

DESCRIPTION

FIG. 1 is a side view of a light with an integrated camera showing my new design;

FIG. 2 is a front view thereof;

FIG. 3 is a back view thereof;

FIG. 4 is a perspective view thereof;

FIG. 5 is a top view thereof; and,

FIG. 6 is a bottom view thereof.

The broken lines of even length shown in the drawings illustrate portions of the exterior of the light with integrated camera that form no part of the claimed design.
